UNITED STATES PATENT OFFICE.

HOMER B. DITWILER, OF MANSFIELD, OHIO.

ARMLET.

SPECIFICATION forming part of Letters Patent No. 321,422, dated July 7, 1885.

Application filed April 9, 1885. (No model.)

To all whom it may concern:

Be it known that I, HOMER B. DITWILER, a citizen of the United States of America, residing at Mansfield, in the county of Richland and State of Ohio, have invented certain new and useful Improvements in Armlets, of which the following is a specification, reference being had therein to the accompanying drawings, in which—

10 Figure 1 represents a plan of my armlet. Fig. 2 shows a section of a spring forming part of the same on a larger scale; and Fig. 3 shows a modified form of fastening.

This invention relates more particularly to 15 that class of armlets or clasps which are used to hold shirt-sleeves in the desired position, but it may be used for other purposes; and the invention consists in the peculiar combination and the construction and arrangement 20 of parts hereinafter more fully described and claimed.

A represents a spiral spring having at its 25 opposite ends caps B B'. In the cap B there is rigidly secured a wire loop, C, which loop has at one end a clasp, D, and at the other a tape or cord, E. This tape is fastened at its other end to a cord, F, by sewing, a knot, or any suitable fastening, which fastening also serves to prevent the tape being drawn through 30 the cap B'. The cord F is carried around to and its free end is passed through the clasp D, which is of such size as to fit the cord rather tightly but yet allow it to slip through for adjustment,

35 It is obvious that a tape or other material may be used for the cord, if preferred, and that instead of using the tape E the cord F may be made long enough to be attached to the loop C, in which case it should be knotted 40 to prevent its slipping through the cap B'.

When under strain, the clasp D assumes the position shown in Fig. 1, whereby the clasp is caused to hold tighter owing to the cord coming in contact with the corner of the clasp.

45 In using this armlet it is only necessary to pull on the end of the cord until the armlet assumes the size of the arm, which it will readily do, as the cord will slip through the clasp until it reaches the proper degree of

tightness when the clasp will hold the cord in 50 place. The spring will yield to accommodate the swelling of the muscles, and thus the sleeve of the wearer will be held securely in the desired position without any strain or stricture on the muscles.

55 In lieu of the clasp shown in Fig. 1, I may use any known form of clasp—such, for instance, as the open clasp with a knotted cord, as shown in Fig. 3.

I do not claim, broadly, a spiral spring with 60 a tape or cord passing through the same to prevent its stretching beyond the desired limit, as I am aware that such a device is old and is shown, for instance, in Patent No. 109,737, dated November 29, 1870.

65 What I claim as new is—

1. The combination, with a spring, A, having a clasp at one end, of a cord connected with the opposite end, having a free end extending outside of said spring and adapted to 70 be held by the clasp, substantially as described.

2. The combination, with a spring, A, having a slip-clasp at one end, of a cord connected with the opposite end, having a free end extending outside of said spring and adapted to 75 be drawn through and be held by said slip-clasp, substantially as described.

3. The combination of a spiral spring, A, with a clasp fast on one end of said spring, 80 and a cord having one end adapted to be held by said clasp and passing through the opposite end of said spring and connected with the end thereof to which the clasp is attached, substantially as described,

85 4. The combination of the spring A, having caps B B', the clasp D, pivotally attached to cap B, and the cord F, connected with said cap and passing through cap B' and having its loose end passed through the clasp D, substantially as described.

90 In testimony whereof I affix my signature, in presence of two witnesses, this 27th day of March, 1885.

HOMER B. DITWILER.
